UNITED STATES PATENT OFFICE

105,507

DESIGN FOR A RADIOGRAPHIC AND FLUOROSCOPIC UNIT

Wilbur S. Werner, South Fort Mitchell, Ky., assignor to The Kelley Koett Manufacturing Company, Incorporated, Covington, Ky.

Application November 3, 1936, Serial No. 65,681

Term of patent 7 years

To whom it may concern:

Be it known that I, Wilbur S. Werner, a citizen of the United States, residing at 63 Dixie Highway, South Fort Mitchell, in the county of Kenton and State of Kentucky, have invented a new, original, and ornamental Design for a Radiographic and Fluoroscopic Unit, of which the following is a specification, reference being had to the accompanying drawing, forming part thereof.

In the two views, the rails upon which the standard supporting the X-ray tube and fluoro-

scopic screen travels, are shown in a fragmentary condition for convenience of illustration.

Figure 1 is a perspective view of a radiographic and fluoroscopic unit showing my new design, with the table in a horizontal position; and

Figure 2 is a perspective view of the same with the table in a vertical position.

I claim:—

The ornamental design for a radiographic and fluoroscopic unit, substantially as shown and described.

WILBUR S. WERNER.
